UNITED STATES PATENT OFFICE.

WILLIAM ARTHUR LOTH, OF PARIS, FRANCE, ASSIGNOR TO SOCIÉTÉ INDUSTRIELLE
DES PROCÉDÉS W. A. LOTH, OF PARIS, FRANCE.

PROCESS FOR THE REPRODUCTION OF THE RECORDED DISPLACEMENTS OR VIBRATIONS
OF A MEDIUM SUCH AS AIR.

Application filed January 3, 1922. Serial No. 526,834.

To all whom it may concern:

Be it known that I, WILLIAM ARTHUR LOTH, citizen of the French Republic, residing at 130 Rue Lecourbe, Paris, France, have invented certain new and useful Improvements in a Process for the Reproduction of the Recorded Displacements or Vibrations of a Medium Such as Air, of which the following is a specification.

10 This invention has for its object a mechanical process for the reproduction of the displacements or vibrations of a medium, such as air, in which use is made, as an intermediary, of a film on which the said displacements or vibrations have been photographically construed in the form of a line; this line represents graphically the composition of the sinusoidal functions, of variable amplitudes, corresponding to each 20 fundamental sound and to its harmonics.

This process is essentially characterized in that use is made for analyzing the film (which is divided by the line in two surfaces, of different thicknesses) a series of 25 exploring styluses the points of contact of which with the film are arranged according to a parallel relatively to the ordinates of the figurative line. These styluses are so hinged that the displacements to which they 30 are subjected, owing to their application on the impressed surface of the film, determine the corresponding displacements either of a diaphragm or of a lamella respectively depending from each of the exploring styluses 35 and the whole of which plays the part of a diaphragm relatively to a stethoscopic chamber, the displacements of this diaphragm determining the vibrations of the air for the reproduction of the recorded 40 sounds.

In the accompanying diagrammatic drawing, given by way of example,

Fig. 1 illustrates, in plan view, a form of carrying out the process forming the subject-matter of the invention.

Fig. 2 is a corresponding side view thereof on an enlarged scale.

Fig. 3 is a perspective view of the arrangement shown in Figs. 1 and 2.

Figs. 4 and 5 are plan and side views respectively of a modification.

Fig. 6 is a cross section of a special recorded film adapted to be used with the means of phonic reproduction of Figs. 1 to 4, with the modification indicated hereafter.

For carrying out the process forming the subject matter of the invention, the surfaces of the film serving as an intermediary and separated by the recorded line or tracing to be reproduced, enlarged or not, have 60 relatively to each other a constant or variable relief in a direction at right angles to the width of the said film. For instance, the film 1 has a constant relief in all the hatched surface 2 limited by the recorded 65 line or tracing 3. This can be obtained by using either a film made of any material, metallic or not, corrugated or not, or a film coated with bichromated gelatin, for instance. Instead of obtaining a surface in 70 relief, it is obvious that an intaglio surface can be employed.

For the reproduction, the film thus made passes under a number of exploring needles 4, having blunt or very fine points, arranged 75 parallel to each other on a common support 5 extending transversely to the direction of unwinding of the said film 1 (Fig. 2).

The needles 4 can rock about the axis 5 arranged transversely to the film 1. The 80 needles control, through rods 6, having the same or different lengths, according to the mode of action adopted, an axis 7 having a groove in which the ends of the rods are engaged. This axis 7 is pivoted at one of 85 its ends 8, whilst its other end 9 fits or is connected to a reproduction diaphragm 10 surmounted by a reinforcing acoustical mouth-piece 11.

The operation is as follows:

Supposing the film 1 presents a surface having a constant relief 2 limited by the recorded line or tracing 3 and that it moves in the direction of the arrow α , each needle 4 coming in contact with the relief surface 2 will be lifted. But, considering that the axis 7 pivoted about its end 8, is engaged at different points by the rods 6 which re-

spectively prolong each of the needles 4, the displacement of the engaging end of each of them will be amplified at the end 9 of the axis 7 engaging the diaphragm 10 in a proportion depending on the distance separating the stem of the needle considered from the joint 8 of the axis 7, the amplification increasing so much the more as the needles 4 nearest the said joint 8 are lifted.

10 It is easy to see that the line or tracing 3 carried by the film 1 and graphically representing the recorded vibrations will determine displacements of the diaphragm 10 which will exactly reproduce the said vibrations. Each needle 4 is lifted only if it comes in engagement with a relief and this lifting imparts to the reproducing diaphragm 10, a displacement equal to that to which has been subjected the corresponding diaphragm during the recording operation.

15 In the modification illustrated in Fig. 6, the film 1 is not provided with an impressed surface, having a constant relief, but the thickness of this surface increases from one 20 of the edges towards the other. For the inclination thus realized, that is to say for the relative heights of the relief at different points, the same conditions as those indicated above are to be applied concerning the 25 mode of construction of the exploring needles 4.

20 In the device shown in Figs. 4 and 5, the diaphragm 10 is constituted by the juxtaposition of resilient lamellæ 10 respectively actuated by the corresponding needles. These lamellæ 10 are mounted on felt bands or strips 12 which permit their displacement and fit on the edge of a stethoscopic cavity 13, for instance. The needles 4 are pivoted 25 on a common axis of rotation 5 which is inclined relatively to the width of the film 1, in the case of a film having an increasing relief as indicated in Fig. 6.

25 Each lifting of a needle 4 varies the inner volume of the chamber 13 which communicates, through acoustical pipes, with listening devices or is provided with an ear-piece 11.

30 The variations of volume of the chamber 13 correspond therefore to the line or tracing 3 carried by the film 1 but, in order that the reproduction may be exact, it is convenient that the displacements to which are subjected the volume of air may have an amplitude proportional to that of the vibrations represented by the graphic tracing carried by the film 1. For that purpose, use is made of a surface having variable reliefs; this surface, as already stated, can be increasing 35 from the edge limiting the film to the figurative tracing 3 on the latter (Fig. 6). By realizing this condition and varying the lever arms actuating the needles 4, the vibrations of the volume of air contained in

the chamber will obviously reproduce exactly the recorded vibrations.

35 Besides, each of them will be reproduced with an amplitude similar to that it had, at the emission, when it actuated the recording diaphragm.

40 In this case, a film having a constant relief, as previously indicated, might also be employed. But, in this case, it is desirable to arrange, between the various needles 4 and the lamellæ 10 constituting the diaphragm and closing the chamber 13, levers which amplify, by observing the rule indicated, the displacements of the said needles 4 and the lengths of which increase from the 45 edge of the film 1 to the analytic line or tracing 3 carried by the latter.

45 For verifying the exactness of the reproduction, a mirror can be mounted on the receiving diaphragm and, by means of a luminous bundle, the spot is projected and its tracing is compared with the standard tracing.

50 What I claim as my invention and desire to secure by Letters Patent is:

55 1. In the installation for the reproduction of movements to which a medium such as air is subjected, a movable surface on which the diagrammatic tracing showing the movements divides the said surface into parts of 60 relatively different heights, the projecting part having a progressively decreasing height from one to the other edge of the surface, needles whose ends engage with the parts of the movable surface, an axis arranged transversely to said movable surface, a reproducing diaphragm, and means to 65 transmit the movements of the needles to the 70 reproducing diaphragm.

75 2. In the installation for the reproduction of movements to which a medium such as air is subjected, a movable surface on which the diagrammatic tracing showing the movements divides the said surface into parts of 80 relatively different heights, the projecting part having a progressively decreasing height from one to the other edge of the surface, parallel needles whose ends engage 85 with the parts of the movable surface, an axis arranged transversely to said movable surface, rods extending the needles beyond 90 their pivot point on the common axis, a reproducing diaphragm, and an intermediate axis arranged transversely with respect to the film, pivoted at one of its ends and the 95 other end acting on the reproducing diaphragm.

100 3. In the installation for the reproduction of movements to which a medium such as air is subjected, a movable surface on which the diagrammatic tracing showing the movements divides the said surface into parts of 105 relatively different heights, the projecting part having a progressively decreasing height from one to the other edge of the surface, 110 parallel needles whose ends engage with the parts of the movable surface, an axis arranged transversely to said movable surface, rods extending the needles beyond 115 their pivot point on the common axis, a reproducing diaphragm, and an intermediate axis arranged transversely with respect to the film, pivoted at one of its ends and the 120 other end acting on the reproducing diaphragm.

125 3. In the installation for the reproduction of movements to which a medium such as air is subjected, a movable surface on which the diagrammatic tracing showing the movements divides the said surface into parts of relatively different heights, the projecting part having a progressively decreasing

height from one to the other edge of the surface, parallel needles whose ends engage with the parts of the movable surface, an axis arranged transversely to said movable surface, rods extending the needles beyond their pivot point on the common axis, a reproducing diaphragm, and an intermediate axis arranged transversely with respect to

the film, pivoted at one of its ends and the other end acting on the reproducing dia- 10 phragm and also provided with a longitudinal groove in which is engaged the outer ends of the needle rods.

In testimony whereof I have affixed my signature.

WILLIAM ARTHUR LOTH.
